CARTRIDGE MAGNETIC TAPE PLAYER OR SIMILAR ARTICLE

Gordon H. Reed, St. Helier, Jersey, Channel Islands, assignor to Television Research Limited, St. Helier, Jersey, Channel Islands, a British company

Filed Aug. 11, 1964, Ser. No. 81,240

Claims priority, application Great Britain Feb. 27, 1964

Term of patent 14 years

(Cl. D26—14)

FIG.1.

FIG.2.

FIG.3.

FIG.4.

FIGURE 1 is a front, top, and right side perspective view of a cartridge magnetic tape player or similar article, showing my new design;

FIGURE 2 is a left side, top, and front perspective view;

FIGURE 3 is a front elevational view; and
FIGURE 4 is a top plan view thereof.

The back and bottom of the article are substantially flat unornamented surfaces with raised edges like the front but omitting the button.

I claim:

The ornamental design for a cartridge magnetic tape player or similar article, substantially as shown and described.
